(Model.)

C. K. GILES.

WATCH CASE.

No. 365,984.

Patented July 5, 1887.

UNITED STATES PATENT OFFICE.

CHARLES K. GILES, OF CHICAGO, ILLINOIS.

WATCH-CASE.

SPECIFICATION forming part of Letters Patent No. 365,984, dated July 5, 1887.

Application filed April 27, 1885. Serial No. 163,658. (Model.)

To all whom it may concern:

Be it known that I, CHARLES K. GILES, a citizen of the United States, residing at Chicago, in the county of Cook and State of Illinois, have invented certain new and useful Improvements in Watch-Cases, which are fully set forth in the following specification, reference being had to the accompanying drawings, in which—

10 Figure 1 is a plan view of a watch-case embodying my invention, a portion thereof being broken away to show the construction; Fig. 2, a sectional view of the same on the line $\alpha\alpha$ of Fig. 1; Fig. 3, a sectional view of the 15 back portion of the case detached, showing the inner bezel hinged thereto; Fig. 4, a similar sectional view of the case-center detached; Fig. 5, an end view of the back portion of the case, with the inner bezel removed at the 20 hinge; Fig. 6, a transverse sectional view of the inner bezel detached, showing the movement-holding ring in position in the bezel; and Fig. 7, an end elevation of the same.

Like letters refer to like parts in all the figures of the drawings.

25 My invention relates to watch-cases, and is in the nature of an improvement upon the combined dust-proof box and case for watches set forth in Letters Patent No. 308,840, granted 30 to me December 2, 1884.

I will now proceed to describe the construction and operation of my invention as I have embodied it in one form, and will then point out definitely in the claims the special improvements which I believe to be new and 35 wish to secure by Letters Patent.

In the drawings, A represents the back portion of the case or box, which may be constructed in one piece, or in two pieces, as shown 40 in Fig. 3 of the drawings, where a represents a ring of base metal, and a' an outer portion or cap of precious metal, the two parts being permanently joined together, however, so as to form practically a single piece. This construction I prefer on account of the economy 45 in the use of precious metal. This back portion A of the case is provided with a flange or projection, A', extending around it about midway of its height, as shown, and at its upper 50 edge is further provided with a groove, a^2 ,

which forms a seat to receive the outer bezel, B, which forms the front portion of the case. This bezel B carries the crystal and snaps into place in the seat a^2 , as shown in Fig. 2 of the drawings, thus forming a dust-proof case to 55 receive the movement. In this form the box or case, consisting of the back portion, A, and upper portion, B, will form a dust-proof box, which may be used for the transportation or exhibition of the movement.

C indicates the case-center, which is annular in form and of sufficient depth to fill the space between the flange A' and the bezel B when the latter is in position, as shown in Fig. 2. This case-center is preferably screw-threaded 65 internally for a portion or the whole of its depth, as shown at c , the upper portion of the part A being correspondingly threaded, as shown at c' , between the seat a^2 and flange A'. By reason of this construction the box may be 70 readily transformed into a case suitable for personal wear by applying the center C over the part A, screwing it into position when screw-threads are used, and then snapping down the bezel B into its seat, the lower edge 75 of the bezel and the flange A' holding the center in place in an obvious manner.

In order to provide a suitable support for the movement whereby it will be securely retained in position and yet be readily inspected, 80 I have devised the following construction:

D indicates a ring or bezel, which is hinged to the upper edge of the lower portion, A, of the case in any suitable manner, the hinge-joint being shown in the present instance as 85 consisting of the perforated lugs d on the bezel, arranged between two similar lugs, d' , on the case A, the whole being connected by means of a pintle, d^2 , passing through all the lugs. Within this bezel D is formed a seat, D', into 90 which the movement-holding ring E snaps. It will be seen that this inner bezel, D, may be readily swung out from the case, carrying with it the movement, which is located in the movement-holding ring E, so that the latter may be 95 inspected or removed, if desired. The bezel may, however, be swung out alone by disengaging it from the ring E, a seat, e , being formed in the interior of the part A near its upper edge, in which the movement-holding 100

ring may rest, as clearly shown in Fig. 2. The hinge-joint connecting the inner bezel, D, with the case is preferably located at the point where the winding-stem enters the case, as shown in Fig. 1, the movement being so arranged within the movement-holding ring E that the winding-stud thereof comes in line with the winding-key of the stem, which latter may be drawn out when it is desired to swing the movement out.

In Letters Patent No. 308,840, hereinbefore specified, there is shown a watch-case consisting of a back and front portion and a case-center clamped between the two. In this construction, however, the body or cylindrical portion of the case forms a part of the front portion of the case, the back consisting of a mere cap, which screws thereto. In this construction the movement is not protected until the entire case—*i. e.*, both the front and back portions—is assembled, since when the movement is placed in the front portion its rear face is exposed. In my present improvement the back portion is adapted to receive the movement, which rests therein, and its exposed portions are completely surrounded by the back portion, which protects it in a great measure even if the front portion be not applied thereto. It is obvious that this will be the case, since the front face of the movement is protected by a plate, while the back face is unprotected, unless completely surrounded by the lower portion of the case, as hereinbefore set forth.

It is obvious that various modifications in the details of construction may be made without departing from the principle of my invention, and I therefore do not wish to be understood as limiting myself strictly to the precise details of construction hereinbefore described, and shown in the drawings. For instance, in order to form a hunter-case watch, the bezel proper, B, may be made somewhat smaller

than in the construction shown in the drawings, and a front plate of ordinary construction will be hinged to the case-center C in such a manner as to cover the said bezel when closed and form a complete hunter-case.

I make no claim in the present application to the subject-matter claimed in an application filed by me of even date herewith, Serial No. 163,660.

Having thus described my invention, what I claim as new, and desire to secure by Letters Patent, is—

1. The combination, with the dust-proof box consisting of the part A, having flange A' and seat a², and the part B, adapted to be sprung or snapped into position in the said seat, of the threaded case-center C, adapted to be screwed upon a correspondingly-threaded portion of the part A, and to be retained in position between the flange A' and the lower edge of the part B, substantially as and for the purposes specified. 65

2. The combination, with a watch-case, of the inner bezel or ring hinged to the case and having a seat to receive the movement-holding ring, substantially as and for the purposes specified. 70

3. The combination, with the back portion, A, of the case, of the bezel D, hinged to its upper edge, and provided with the seat D', into which the movement-ring may be sprung or snapped, substantially as and for the purposes specified. 75

4. The combination, with the part A, of the outswinging bezel D, hinged thereto and carrying the movement-holding ring, the part A being provided with a seat, e, in which the movement-holding ring rests when in position, substantially as and for the purposes specified. 80

CHARLES K. GILES.
